TAKE-DOWN FIREARM

Edwin Pugsley, New Haven, Conn., assignor to
 Winchester Repeating Arms Company, New
 Haven, Conn., a corporation of Maryland

Application June 16, 1936, Serial No. 85,476

6 Claims. (Cl. 42—75)

This invention relates to an improvement in firearms and particularly to firearms of the take-down type, i. e., firearms in which a butt-unit and a barrel-unit are readily separable one from 5 the other for convenience in packing, shipping and carrying.

One of the objects of the present invention is to provide a take-down firearm with superior coupling-means for attaching the two 10 units of the firearm together characterized by simplicity, ruggedness and effectiveness.

Another object is to provide superior quick-acting coupling-means by which the separable units of a take-down firearm may be coupled 15 and uncoupled.

With the above and other objects in view, as will appear to those skilled in the art from the following, considered in conjunction with the accompanying drawings and appended claims, 20 the present invention includes all features disclosed therein which are novel over the prior art.

In the accompanying drawings:

Fig. 1 is a broken view in side elevation of a 25 take-down firearm embodying the present invention;

Fig. 2 is a broken view mainly in side elevation and partly in vertical central longitudinal section with the two units of the firearm shown 30 as coupled together;

Fig. 3 is a view corresponding to Fig. 2 but showing the two units of the firearm partly separated preparatory to their complete separation or take-down;

Fig. 4 is a broken top or plan view;

Fig. 5 is a broken transverse sectional view taken on the line 5—5 of Fig. 2;

Fig. 6 is a similar view taken on the line 6—6 of Fig. 3;

Fig. 7 is a transverse sectional view taken on the line 7—7 of Fig. 2;

Fig. 8 is a broken longitudinal sectional view taken on the line 8—8 of Fig. 2;

Fig. 9 is a view mainly in side elevation and 45 partly in vertical central section of the rear portion of the barrel-unit frame-member;

Fig. 10 is a view in side elevation of the butt-unit frame-member;

Fig. 11 is a perspective view of the coupling- 50 lever looking mainly toward the under side thereof;

Fig. 12 is a perspective view of the coupling-post; and

Fig. 13 is a perspective view of the coupling- 55 abutment nut.

The particular take-down firearm herein chosen for illustration includes two major units which are separable one from the other to enable the firearm to be more conveniently packed, shipped or carried. The rear unit of the firearm may for convenience of description be designated as the butt-unit and comprises in the main a buttstock 20 and a butt-unit frame-member 21 rigidly coupled to the said buttstock. The complementary front unit of the 10 firearm, designated for convenience of description as the barrel-unit comprises in the main a barrel 22, a barrel-unit frame-member 23 and a forestock 24 removably secured to the under side of the said barrel. The butt-unit frame-member 21 and the barrel-unit frame-member 23 are adapted to interfit to provide a complete frame or receiver for the firearm. 15

The barrel-unit frame-member 23 throughout the major portion of its length is of inverted U- 20 shaped form in cross-section and includes a cylindrically-contoured upper wall 25, complementary side walls 26—26 and a rear wall 27, the lower edge of which latter terminates at a point above the lower edges of the side walls 25 26—26.

The butt-unit frame-member 21 includes a body-portion 28 against the forward face of which the rear edge of the frame-member 23 is adapted to abut. The frame-member 21 also 30 includes a forwardly-extending tang 29 which fits between the side walls 26—26 of the barrel-unit frame-member 23 and partly closes the open lower end thereof. Formed at the junction of the body-portion 28 and the tang 29 of the frame-member 21 is a trigger-guard or loop 30 in which is located a trigger 31. 35

Projecting rearwardly and slightly downwardly from the rear wall 27 of the barrel-unit frame-member 23 is a coupling-post or stem 32 which 40 is attached to the said rear wall 27 by being provided with an integral forwardly-extending threaded stud 33 fitting into a threaded bore 34 in the said rear wall 27. The said coupling-post 32 is adapted to project into a slightly-sloping bore or passage 35 formed adjacent the upper end of the body-portion 28 of the butt-unit frame-member 21 and extending from front 45 to rear therethrough. The rear end of the said coupling-post 32 is formed with an externally-threaded integral stud 36 upon which is mounted a coupling-nut 37 and a cup-shaped lock- or jam-nut 38 having in its rear face a kerf 39 or otherwise provided with means by which it may be turned upon the stud 36. The coupling- 50 55

nut 37 is of conical form and its forward face constitutes an adjustable coupling-abutment 40 as will hereinafter appear. For convenience in adjusting the coupling-nut 37 upon the stud 36 of the post 32, the said nut is provided in its periphery with an annular series of slots 41 adapted to receive a suitable instrument by means of which the said nut may be turned.

The adjustable coupling-abutment 40 formed by the forward face of the coupling-nut 37 is adapted to be engaged by a cam-lip 42 formed upon a cylindrical stem 43 rigidly offsetting from a coupling-lever 44. The cam-lip 42 just referred to is formed by providing the under face 15 of the stem 43 of the lever 44 with a diametrical clearance-groove 45 of cylindrical contour in cross-section, which groove extends at a right angle to the longitudinal axis of the coupling-lever 44, as particularly well shown in Fig. 11.

20 The cylindrical stem 43 of the coupling-lever 44 is mounted for oscillating movement in a cylindrical bearing-opening 46 extending from the upper surface of the body-portion 28 of the frame-member 21 inwardly to the longitudinal bore or passage 35 therein. To retain the stem 43 and hence the coupling-lever 44 in place, the said stem has radially threaded into its inner end a retaining-screw 47 which is accessible for installation and removal through the counter-bored forward end 48 of the bore 35 which serves to snugly receive the base-portion 49 of the coupling-post 32.

The coupling-lever 44 is adapted to oscillate through an arc of substantially 90° upon the upper face of the body-portion 28 of the frame-member 21 and is provided with a stop-finger 50 engaging a stop-abutment 51 formed upon the adjacent portion of the upper wall of the frame-member 21, as clearly indicated in Fig. 4. The engagement of the stop-finger 50 with the stop-abutment 51 serves to limit the movement of the coupling-lever 44 when the same reaches a position as indicated by full lines in Fig. 4, in which it is aligned with the gun-structure. To yieldingly retain the coupling-lever in the position referred to, it is provided on its rounded forward edge with a detent-pocket 52 receiving a detent-plunger 53 mounted in a rearwardly-opening bore 54 in the upper portion of the frame-member 21, as clearly shown in Fig. 2. The detent-plunger 53 (Fig. 2) is resiliently forced into engagement with the adjacent surface of the coupling-lever 44 by a helical spring 55 also located in the bore 54 before referred to.

55 When the coupling-lever 44 is swung laterally, as indicated by broken lines in Fig. 4 and by full lines in Fig. 6, to permit the uncoupling of the two units of the firearm, the detent-plunger 53 also serves to yieldingly retain the said lever 44 in this position by engaging with a detent-recess 56 (Fig. 3) also formed in the coupling-lever 44 at a position substantially 90° removed from the detent-recess 52 therein before referred to.

65 When the coupling-lever 44 which is provided at its free end with an upstanding thumb-piece 57, is aligned with the firearm-structure as indicated particularly well in Figs. 1, 2, 4, and 5, the cam-lip 42 of its rigid stem 43 is in jamming engagement with the forward or coupling-abutment face 40 of the coupling-nut 37, which latter is securely locked in a previously-adjusted position by the lock-nut 38. Under these conditions the co-action of the cam-lip 42 and the coupling-abutment 40 serves to rigidly and securely hold

the barrel-unit frame-member 23 in normal and proper relationship with respect to the butt-unit frame-member 21 and hence couples together the entire butt-unit and the entire barrel-unit in position to constitute a complete usable firearm. 5

When the coupling-lever 44 is swung into its uncoupling position in which it is indicated by full lines in Figs. 3 and 6 and by broken lines in Fig. 4, the cylindrical stem 43 of the said coupling-lever is similarly turned with the result 10 that the cam-lip 42 thereof is disengaged from the coupling-nut 37 and the clearance-groove 45 in the lower end of the said stem is turned so as to extend in a direction from front to rear of the firearm-structure and hence substantially 15 parallel with the path of movement in which the coupling-nut 37 must move as the two units of the firearm are separated by drawing them apart in an axial direction. During the initial axial 20 separation of the two units the upper portion of the coupling-nut 37 will pass through the rear portion of the clearance-groove 45 in the stem 43 in a path which is inclined slightly downward with respect thereto.

In Fig. 3 of the drawings, the butt-unit and the barrel-unit are shown as partly separated and it should be noted that owing to the inclination of the stem 43 of the coupling-lever 44 that the coupling-nut 37 moves beneath the said stem 43 of the coupling-lever 44 after it has been moved but a relatively short distance forwardly by the separation of the two units in the direction indicated in Fig. 3. After the two units have reached the positions in which they are shown in the figure just referred to they are free to be completely separated by moving the frame-member 23 forwardly and slightly upwardly with respect to the butt-unit frame-member 21.

By means of the construction and arrangement of parts above described, the simple turning movement of the coupling-lever 44 serves to free the two separable units of the firearm and permit the same to be "taken down," so to speak. After the two units of the firearm have been re-assembled and the coupling-lever 44 is swung back into its normal position in which it is aligned with the longitudinal axis of the firearm, the cam-lip 42 of the cylindrical stem 43 of the said lever will positively engage the forward face of the coupling-nut 37 with a sufficiently-firm jamming action to insure that the two frame-members 21 and 23 of the firearm will be firmly seated together.

Both for the initial adjustment and for subsequent adjustment, should wear occur, the coupling-nut 37 may be adjusted upon the stem 36 of the coupling-post 32, after the locking-nut 38 has been loosened, by an instrument inserted through clearance-openings 58, one of which is formed in the respective side walls of the body-portion 28 of the butt-unit frame-member 21. The adjustment referred to must be effected while the butt-stock 20 is disconnected from the frame-member 21, since the said buttstock covers the openings 58 when the gun is completely assembled. The lock-nut 38 may be loosened or tightened by a screw driver or similar instrument inserted through the rear end of the bore 35 in which the coupling-post 32 normally extends.

The invention may be carried out in other specific ways than those herein set forth without departing from the spirit and essential characteristics of the invention, and the present em- 75

bodiments are, therefore, to be considered in all respects as illustrative and not restrictive, and all changes coming within the meaning and equivalency range of the appended claims are intended to be embraced therein.

I claim:

1. A take-down firearm including in combination: a butt-unit having a frame-member organized therewith; a barrel-unit separable from the said butt-unit and having a rigid frame-member interfitting with the frame-member of the said butt-unit; the frame-member of one of the said units being provided with a threaded portion for the reception of an adjustable coupling-abutment; and releasable coupling-means for holding the two said units in assembled relationship, including a threaded coupling-abutment having threaded engagement with the aforesaid threaded portion of one of the frame-members, the said coupling-means also including an oscillating coupling-lever mounted on the exterior surface of the frame-member complementing the frame-member carrying the said coupling-abutment, the said coupling-lever having a rigid coupling-cam directly engageable with the said threaded coupling-abutment.

2. A take-down firearm including in combination: a butt-unit having a frame-member organized therewith; a barrel-unit separable from the said butt-unit and having a rigid frame-member provided with a threaded portion for the reception of an adjustable coupling-abutment and interfitting with the frame-member of the said butt-unit; and releasable coupling-means for holding the two said units in assembled relationship, the said coupling-means including a threaded coupling-abutment having threaded engagement with the threaded portion of the frame-member of the said barrel-unit, the said coupling-means also including an oscillating coupling-lever mounted on the exterior surface of the frame-member of the said butt-unit and having a rigid coupling-cam directly engaging the threaded coupling-abutment of the frame-member of the said barrel-unit.

3. A take-down firearm including in combination: a butt-unit frame-member; a barrel-unit frame-member separably interfitting with the said butt-unit frame-member and having a threaded portion; and releasable coupling-means for holding the two said frame-units in assembled relationship including an adjustable coupling-abutment having threaded engagement with the threaded portion of the said barrel-unit frame-member, the said coupling-means also including an oscillating coupling-lever having a rigid stem offsetting therefrom provided with a coupling-cam directly engaging the adjustable coupling-abutment of the said barrel-unit frame-member.

4. A take-down firearm including in combination: a butt-unit frame-member having a lon-

gitudinal bore therein; a barrel-unit frame-member separably interfitting with the said butt-unit frame-member and having a threaded portion adapted to extend into the longitudinal bore of the said butt-unit frame-member; and releasable coupling-means for holding the two said frame-members in assembled relationship, including a threaded coupling-abutment having threaded engagement with the threaded portion of the said barrel-unit frame-member and extending into the bore in the said butt-unit, the said coupling-means also including an oscillating coupling-lever having a stem projecting also into the longitudinal bore of the said butt-unit frame-member and having a rigid coupling-cam directly engaging with the threaded coupling-abutment of the barrel-unit frame-member.

5. A take-down firearm including in combination: a butt-unit frame-member having a longitudinal bore and one or more openings leading laterally from the said bore; a barrel-unit frame-member separably interfitting with the said butt-unit frame-member and having a threaded portion extending into the longitudinal bore therein; and releasable coupling-means for holding the two said frame-members in assembled relationship, including an adjustable coupling-abutment having threaded engagement with the threaded portion of the said barrel-unit frame-member, the said coupling-means also including an oscillating coupling-lever having a stem projecting into the longitudinal bore of the said butt-unit frame-member and having a rigid coupling-cam directly engaging with the threaded coupling-abutment of the barrel-unit frame-member.

6. A take-down firearm including in combination: a butt-unit frame-member having a forwardly-facing portion and a rearwardly-facing portion and a longitudinal bore extending between and intersecting both the said forwardly-facing portion and the said rearwardly-facing portion of the frame-member; a barrel-unit frame-member separably interfitting with the said butt-unit frame-member and having an externally-threaded coupling-projection extending into the longitudinal bore of the said butt-unit frame-member; and coupling-means for holding the two said frame-members in assembled relationship including an internally-threaded coupling-abutment adjustably mounted upon the externally-threaded coupling-projection of the said barrel-unit frame-member, the said coupling-means also including an oscillating coupling-lever mounted on the exterior surface of the said butt-unit frame-member and having a stem extending into the longitudinal bore in the said butt-unit frame-member and provided with a coupling-cam directly engaging with the coupling-abutment on the coupling-projection of the said barrel-unit frame-member.

EDWIN PUGSLEY.
